SPRAY OILER

Harold L. Schlosser, Defiance, Ohio, assignor to
Lectrolite Corporation, Defiance, Ohio, a corporation of Ohio

Application April 9, 1936, Serial No. 73,482

1 Claim. (Cl. 299—95)

An object of my invention is to provide a spray oiler which is simple, durable and comparatively inexpensive to manufacture.

A further object is to provide a spray oiler of compact design comprising a container for oil or the like, and a fitting associated therewith having a discharge nozzle for sprayed oil, an intake valve for compressed air for placing the contents of the container under pressure, an intake tube depending within the container, and a control valve for the flow of oil, the container having a supporting handle adjacent to which the control element of a control valve is located for convenience in controlling the flow of oil from the container to the nozzle.

A still further object is to provide a nozzle construction which is adjustable for producing either a needle spray or a wide spiral spray, the nozzle being also adjustable to intermediate positions for thereby adjusting the spread of the spiral spray.

With these and other objects in view, my invention consists in the construction, arrangement and combination of the various parts of the device, whereby the objects contemplated are attained, as hereinafter more fully set forth, pointed out in my claim, and illustrated in the accompanying drawing, in which:

Figure 1 is a side elevation of my spray oiler with the container shown in section.

Figure 2 is an enlarged, vertical, sectional view through the fitting at the top of the container and the nozzle connected therewith.

Figure 3 is a sectional view on line 3—3 of Figure 2.

Figure 4 is a sectional view of the nozzle on a still larger scale showing the parts in a different position than Figure 2.

Figure 5 is an enlarged perspective view of a bushing used in the nozzle.

Figure 6 is a sectional view similar to the left end of Figure 2, showing a modified construction; and

Figure 7 is an enlarged sectional view on the line 7—7 of Figure 6.

On the accompanying drawing I have used the numeral 10 to indicate a container for oil or the like 12. A handle 14 is welded to the container 10 for the purpose of conveniently supporting the spray oiler when it is in use.

Soldered or brazed in the top of the container 10 is a threaded bushing 16. A nozzle fitting, generally referred to as A, is threaded in the bushing 16. The fitting A comprises a body portion 18, a nozzle sleeve 20 having a second nozzle

sleeve 22 threaded thereon, a control valve body 24, and an intake valve 26 for compressed air. The sleeves 20, 24 and 26 are screw threaded into the body member 18.

The fitting 26 includes an ordinary tire valve 28 and a dust cap 30. The dust cap can be removed and a tire chuck engaged with the fitting 26 to introduce compressed air into the container 10 through a passageway 32, which, as shown in Figure 3, is independent of the bore 34 of the member 18. The bore 34 has communicating therewith an intake pipe 36 depending within the container 10 and terminating in a strainer or screen 38 adjacent the bottom of the container.

The nozzle sleeve 22 is provided with a discharge orifice 40 and is packed relative to the sleeve 20 by a spring urged packing 42. Within the sleeve 22 I provide a bushing 44 having an oil passageway 46 and a spiral groove 48 in the periphery of the bushing and by-passing the passageway 46.

A point element 50 is mounted in the outer end of the sleeve 20 and is adapted for seating against the edge of the passageway 46, as shown in Figure 4. The point element is suitably perforated to permit the passage of oil therethrough when the point element is so seated.

For coaction with the inner end of the sleeve 20 I provide a valve member 52 normally seated by a spring 54. This valve may be unseated by a lever 56 which, when pushed downwardly as indicated by the arrow a in Figure 1, retracts a stem 58 connected with the valve member 52. Suitable packing is provided at 60 to prevent leakage of oil around the stem 58.

In Figures 6 and 7 I show a modified construction which eliminates the necessity of providing the bushing 44 with its spiral groove 48. In these figures a fitting A' is illustrated, having a sleeve 20a terminating in a pointed or tapered element 50a. A groove 48a is formed in the inclined portion of the pointed element 50a, the cross section of the groove being shown in Figure 7.

A tapered bore 46a of a head 22a is machined at the same angle as the pointed element 50a, so that when the head 22a is screwed onto the sleeve 20a as far as it will go, the surfaces 46a and 50a seat relative to each other.

Practical operation

The fittings A or A' can be removed for partially filling the container 10 with oil. The fitting may then be replaced and air introduced through the fitting 26, thus placing the contents

- of the container under pressure. Subsequently when the valve 52 is opened, with the parts in the position of Figures 2 or 6, a needle spray will result. The passageway 46 in Figure 2, or 5 the space between the tapered point 50a and the bore 46a, offer less resistance to the flow of oil than the annular grooves 48 or 48a, and consequently the oil flows around the points 50 or 50a, and then through the nozzle openings 40 or 40a, 10 resulting in a needle spray b or b', as indicated in Figures 2 and 6.
- When the point 50 is seated, as in Figure 4, however, the oil must travel through the spiral groove 48 and in so doing rotation is imparted 15 to it and centrifugal force causes the spray to come out in a cone shape, as indicated at c. By partially closing the point element against the passageway 46, the degree of spread of the spray c can be regulated.
- 20 When the point element 50a is seated against the bore 46a, the oil must travel through the spiral groove 48a, and in so doing, rotation is imparted to the oil with the type of nozzle shown in Figure 6, thereby resulting in centrifugal force causing the spray to assume the shape shown in Figure 4. Obviously the point element 50a also can be partially closed relative to the bore 46a.
- Some changes may be made in the construction and arrangement of the parts of my device 30 without departing from the real spirit and pur-

pose of my invention and it is my intention to cover by my claim any modified forms of structure or use of mechanical equivalents which may be reasonably included within their scope.

I claim as my invention:

In combination with a container for oil or the like, a fitting connected with the top thereof and comprising the following elements: a nozzle projecting horizontally in one direction therefrom, a control valve for controlling the flow of 10 fluid from said container to said nozzle and having a stem, an operating lever pivoted to said control valve stem, projecting horizontally in the opposite direction from said fitting and having a projection engaging the end of the control 15 valve, an intake pipe connected with the bottom of said fitting, depending within said container and terminating adjacent the bottom thereof and an intake check valve at the top of said fitting for receiving compressed air and discharging 20 it into said container, and a handle on said container so located with respect to said lever that said lever may be readily swung about its pivotal connection with the thumb when said container is being carried by means of said 25 handle whereupon said projection engages said control valve and effects pulling of said control valve stem outwardly relative thereto and thereby opening of said control valve.
